UNITED STATES PATENT OFFICE.

LOUIS C. EDGAR, OF SWISSVALE, AND ADOLF SUTER, OF BEAVER, PENNSYLVANIA.

FURNACE-VALVE-OPERATING MECHANISM.

1,192,176.

Specification of Letters Patent. Patented July 25, 1916.

Application filed May 22, 1914. Serial No. 840,396.

To all whom it may concern:

Be it known that we, LOUIS C. EDGAR, of 2022 Hampton avenue, Swissvale, in the county of Allegheny and State of Pennsylvania, and ADOLF SUTER, of 1100 Sixth street, Beaver, in the county of Beaver and State of Pennsylvania, have invented certain new and useful Improvements in Furnace-Valve-Operating Mechanisms, of which the following is a specification.

Our invention relates to the construction and arrangement of mechanism for manipulating the valves of Siemens regenerative furnaces, and, while not restricted to such uses, the invention more particularly relates to the construction and arrangement of mechanism used in operating and controlling the movement of the reversing and damper valves of regenerative furnaces using producer gas as fuel.

Our invention is shown as applied to valves of the lifting type, although broadly adapted for use with any of the various known types of such valves.

One object of the invention is to provide a valve operating mechanism whereby the necessity of separately and independently operating the series of valves is avoided in opening and closing the valves, and to provide means for simultaneously manipulating the valves and for independently adjusting each valve without interruption of or interference with the cycle of operations followed in the valve reversing operations.

Another object of our invention is to provide a valve operating mechanism having novel means enabling the volume or quantity of burned gases or products of combustion passing through the air and the gas regenerators, in heating the regenerators, to be increased or lessened.

A further object of the invention is to provide a valve operating and controlling mechanism having improved means whereby the quantity of the burned gases or products of combustion used in heating the air relative to the quantity used in heating the gas regenerators is varied as is found necessary or desirable.

Another object of this invention is to provide a valve manipulating mechanism having novel means whereby the valves of a re-

generative furnace are made simultaneously operable in timed relation in opening and closing and are independently regulable and controllable to vary the extent of opening and closing movement of the valves.

A further object of our invention is to provide a reversing-valve operating mechanism having means whereby, when set in motion, the series of valves are mechanically actuated to reverse the direction of flow of air and fuel gas and of the products of combustion through the regenerators and furnace and are automatically brought to rest at the end of such reversing operation.

Another object of our invention is to provide a valve operating mechanism for regenerative furnace valves, having novel means by which the valves of a series of valves are independently adjusted as to the extent of opening movement and are always opened from and returned to a fully closed position.

A further object of the invention is to provide a damper valve operating mechanism with a novel arrangement of flexible connections for varying the stroke of the valves to change the extent of lifting movement thereof without interference with the opening and closing movements or change in the closed position of the valves.

A still further object of the invention is to provide a valve operating mechanism by which the travel of the air damper valves may be varied without change or interruption in the opening and closing movement of the other valves operatively connected to the operating mechanism.

Our invention still further consists in the novel arrangement and construction of parts, as will become more fully apparent in the specification and appended claims.

Referring now to the drawings forming part of this specification, Figure 1 is a plan showing our improved valve operating mechanism as applied to the gas, air and stack flues of a regenerative open hearth furnace. Fig. 2 is an elevation, partly in section, of the apparatus shown in Fig. 1. Fig. 3 is a plan showing on an enlarged scale, the valve operating mechanism forming part of this invention and illustrated in Figs. 1 and 2. Fig. 4 is a side elevation of the valve oper-

ating mechanism shown in Fig. 3. Fig. 5 is an end elevation of the apparatus shown in Figs. 3 and 4. Fig. 6 is a sectional elevation, showing the valves located between the 5 air regenerator flues and the furnace stack flue, with the floating sheave construction for regulating the opening and closing movement thereof and the operating mechanism therefor. Fig. 7 is an elevation showing, 10 diagrammatically, the operating connections between the damper valves located between the air regenerators and the stack flue and the valve operating mechanism. Fig. 8 is a 15 similar elevation, showing diagrammatically, the connections between the air damper valves and operating mechanism therefor. Fig. 9 is a diagrammatic elevation similar to those of Figs. 7 and 8 showing the connections between the gas valves, and 20 the combustion valves, and the operating mechanism for reversing and adjusting the stroke or travel of these valves. Fig. 10 is a sectional elevation on a larger scale showing a detail in the construction of the adjusting mechanism, by which the extent of 25 movement of the gas and combustion valves is regulated and controlled. Fig. 11 is a transverse section of the same. Fig. 12 is a sectional elevation, on a larger scale showing 30 a detail in the construction of the bell cranks forming part of the air damper valve adjusting mechanism. Fig. 13 is an enlarged transverse section of the same, the section being taken on the line XIII—XIII 35 of Fig. 12. Fig. 14 is a sectional plan on a larger scale, showing the construction of the drums and friction operating mechanism by which the damper valves for the air regenerators are adjusted. Fig. 15 is a sectional elevation of the floating sheave mechanism 40 forming a novel part of this invention and shown as part of the air regenerator damper valve operating mechanism, the section being taken on the line XV—XV of Fig. 6. Fig. 16 is a side elevation showing 45 a detail in the arrangement of the limit switches by which the operation of the driving motor is regulated and controlled.

In the accompanying drawings, the numeral 2 designates the gas regenerator chamber and 50 3 the air regenerator chamber at one, (the left hand), end and 4 and 5 denote respectively, the gas and air regenerator chambers at the opposite, (or right hand), end of a regenerative furnace. Up- 55 take flues, (not shown), of the usual construction, are employed at the ends of the furnace to separately connect each of the regenerator chambers 2, 3, 4, 5 (which are located below the bottom of the furnace), 60 with the interior of the furnace or furnace hearth.

The gas regenerator chambers 2 and 4 are connected by horizontal flues 6 and 7, to

the lower ends of vertical flues 8 and 9 and 65 the air regenerator chambers 3 and 5, by horizontal flues 10 and 11, to the lower ends of vertical flues 12 and 13 (see Fig. 2). The horizontal flues 10 and 11 also connect at 70 one end, into a horizontally extending main stack flue 14 which leads into the furnace stack 15.

Located at one side of the vertical gas flue 8 is a vertical gas flue 16 which is connected, at its lower end, by a horizontal gas flue 17, 75 with the lower end of a vertical gas flue 18 and located at one side of the vertical gas flue 9 is a vertical gas flue 19 which is connected at its lower end by a horizontal gas flue 20 with the lower end of a vertical gas flue 21. The 80 flues 18 and 21 are connected, at their upper ends, to overhead gas mains (not shown) by which fuel gas is conducted to the furnace from the gas producers or other place of supply. Also located on one side of the 85 vertical flues 8 and 9 are vertical flues 22 and 23, which connect at their lower ends into horizontal flues 24 and 25, leading to the horizontally extending main stack flue 14, the flues 22 and 24, or 23 and 25 serving 90 alternately to conduct the burned gases or products of combustion from the reversing valves to the stack flue 14 which is connected at its discharge end to the furnace stack 15. Each of the sets of vertical flues 8, 16, 22, 95 and 9, 19, 23 is surmounted by a reversing valve, of the lifting type, (see Fig. 2) by which the inward flow of unburned gases to the gas regenerators 2, 4, and the outward flow of burned gases or products of combustion from the regenerators 2 and 4 to the stack flue 14 and stack 15, is regulated and controlled. The vertical flues 12, and 100 13, (Fig. 2) connected to the flues 10 and 11 leading to the air regenerator chambers 2 105 and 5, have air valves 28, 29 at their upper ends by which the supply of air to the air regenerators is regulated and controlled.

A vertical damper valve 30, located in the main stack flue 14 adjacent to the stack 15, is 110 provided to regulate and control the stack draft on the furnace. Similar damper valves 31 and 32 provide means in the flues 10 and 11 to shut off either of these flues from the main stack flue 14, the closed one 115 of the flues 10, or 11 being used at such time to supply air to the air regenerator 3 or 5 with which it connects and the open one affording means for conducting to the stack 15, the products of combustion from the air 120 regenerator with which it connects. Each of the reversing valves comprises a base 33, a casing or hood 34 and two hollow water cooled lifting buckets forming water cooled lifting valves. The base 33 and the top of 125 the casing 34 have registering openings therein and surrounding each of the two openings in the top of the casing is a con-

centric upwardly extending flange forming an annular pocket 35 for the water seal. The water cooled buckets each have a depending flange 36 which projects down-
wardly into the pocket or water seal 35.

The base 33 of the valve casing has up-
standing marginal flanges, which, with the upwardly extending flanges of the opening through the base, form a water seal 37 for
10 the lower marginal edge of the casing 34 and for the lower edges of the valve buckets. Each valve bucket is provided with a series of lugs or ears 38 by which the buckets are fastened through adjusting rods to a yoke
15 39, connected to one end of a flexible lifting or operating connection such as a rope or cable. The flanged openings in the base 33 of the valves are formed to register with the open upper ends of the sets of vertical gas
20 flues 8, 16, 22, and 9, 19, 23, the upper ends of these flues terminating at about the floor level of the pit which is located on the charging side of the furnace, beneath the charging floor 40. The air valves 28 and 29 are of
25 the mushroom type and are suspended above valve rings 41 with which the vertical air flues 12 and 13 are capped at about the floor level of the pit. The stack damper valve 30 in the flue 14 and the air dampers 31 and 32
30 within their respective flues 10, and 11 are rectangular in cross section and are suspended within the flues so as to slide vertically therein, suitable grooves or recesses being formed in the sides of the flues to pro-
35 vide guideways for these valves. As has been stated the valves are located in the pit in front of or on the charging side of the furnace, beneath the furnace charging floor 40, and mounted upon the charging floor,
40 above the pit, is the base 42 of the valve operating mechanism forming part of this invention.

Secured on the base 42 of the valve operating mechanism (see Figs. 3, 4 and 5) is
45 a series of capped pedestal bearings 43, 44, 45, in which the crank shaft 46 is rotatably mounted, and also mounted on the base 42 is the worm wheel casing or housing 47 for the worm and worm wheel used in actuating
50 the crank shaft 46 of the valve operating mechanism, this casing 47 being provided with bearings 48 and 49 which engage and assist in supporting the crank shaft 46. In the construction shown, the vertical axial
55 center of the crank shaft 46 of the operating mechanism is in the same vertical plane as the vertical center line of the main stack flue 14 as will be seen by reference to Fig. 1. The lower portion of the casing 47 is pro-
60 vided with bearings 50, 50, in which the driving worm shaft 51 is mounted, and a worm 52, formed integrally on this shaft as shown, operatively engages with the teeth of the mutilated worm wheel 53, which is

mutilated by omitting part of the teeth on 65 the periphery thereof, which is keyed or otherwise fastened to the crank shaft 46 within the housing 47.

Secured on an extension 54 of the base 42 is a reversing electric driving motor 55 having one end of its armature shaft connected to the worm shaft 51 by a flange coupling 56. The commutator end of the armature shaft is provided with a band brake wheel 57, which is operatively engaged by a brake band 58. The brake band 58 is secured to the extension 54 of the base 42 and is operatively connected to the core of a solenoid 59 also mounted on the extension 54. The crank shaft 46 is provided with a crank 60, 80 by which the combustion valve buckets 61 and 62, which close the vertical flues 22 and 23 leading from the gas valves to the stack flues 24, 25, are actuated, and with a crank 63, by which the gas valve buckets 64 and 65, 85 for closing the two vertical flues 16 and 19 which connect the fuel gas flues 18 and 21 with the gas regenerator flues 6 and 7, are actuated. The shaft 46 is also provided near one end with a double grooved sheave wheel 90 66, which is turned by the shaft in opening and closing the sliding valves 31 and 32 in the flues 10 and 11, and on one end of the shaft 46, is a crank disk 89 by which the mushroom or air damper valves 28 and 29 95 are operated in opening and closing.

Mounted at one end and on opposite sides of the base 42 are brackets forming pivot bearings 68, 69 for the bell cranks 70 and 71 by which the mushroom air valves 28 and 29 100 are moved and the extent of movement in opening and closing is regulated. Located beneath the furnace charging floor 40 and above the floor of the pit in which the various valves are erected is a platform 72 supporting a series of sets of bearing stands 73, 74, 75, 76 these sets of stands being arranged in pairs. Each pair of stands 74—74 and 75—75 (see Figs. 2 and 4) has a bell crank, 110 77 or 78 pivotally mounted thereon, through which the buckets 62, 64 of the reversing valves are operated, and each pair of stands 73—73 and 76—76 has one end of one of the lever arms 79 or 80 pivoted thereto, these arms forming connecting means by which 115 the buckets 61 and 65 of the reversing valves are opened and closed.

The bell crank 77 and lever arm 80 on the platform 72 are pivotally connected by means of a connecting rod 81 so as to swing 120 or rock in unison, and the bell crank 78 and lever 79 are pivotally connected in a similar manner by a connecting rod 82. By connecting the bell crank 77 with the lever arm 80 and the bell crank 78 with the lever arm 125 79 in this manner, the gas valve bucket 65 closes when the gas valve bucket 65 opens and vice versa, and the combustion valve

bucket 61 opens when the combustion valve bucket 62 closes and closes when the bucket 62 opens. The outer end of the arm 83 of the bell crank 77 is operatively connected by a reach rod 84 to the crank 60 on the crank shaft 46 and the outer end of the arm 85 of the bell crank 78 is connected by a similar connecting rod 86 to the pin of the crank 63 on the crank shaft 46. The cranks 60 and 63 are located on the shaft 46 in the same plane so that both cranks are either in extreme low position, or extreme high position. One arm 87 of the bell crank 70 on one end of the base 42 is operatively connected to the crank pin 88 on the crank disk 89 forming part of the crank shaft by means of a connecting rod 90. The arms 87 and 91 of the bell cranks 70, 71 are connected together by a rod 92 so as to always swing or rock the bell cranks in unison when the crank shaft 46 is oscillated or rotated.

The bell cranks 70, 71 located above the charging floor and the other bell cranks 77, 78 and also the lever arms 79, 80 beneath the charging floor 40 are adjustably secured to one end of the flexible connections leading to the gas, combustion or air valve operated by each of the respective bell cranks and levers as will be explained. The arms of the bell cranks 70 and 71 operating the air valves 28, 29 are hollow or recessed and mounted in the recess 93 of these arms, which forms a track, is a wheeled trolley (see Figs. 12 and 13). These trolleys comprise a threaded nut 94 through which an adjusting screw 95 extends and formed integrally on opposite sides of the nuts are stub shafts or trunnions upon which wheels 97, 97 are rotatably secured. Mounted on each trunnion between each wheel 97 and the adjacent side of the nut 94 is a bar or plate 98 having a hole therein through which a trunnion of the nut 94 extends. The opposite end of the plates 98 are secured to a separator block 99 by bolts 100, this separator having a longitudinal opening by which one end of a rope, cable or like flexible member is secured to the trolley. The adjusting screws 95 in the nuts 94 extend outwardly through an opening in the outer end of the arm 70 or 71 and through a swivel support 101 which is secured in the openings therefor in the lugs 102, 102 on the outer end of the arms 70 and 71. The outer end of the adjusting screw 95 is provided with hand wheels 103 or 104 by which the screws are turned in moving the nuts 94 lengthwise in the recess 102 in the arms 70 or 71. It should be noted that the trolleys are movable lengthwise within the recess of the hollow arms of these bell cranks into a position in which the axial center of the wheels 97 on the trolley are in alignment with the center of the pivotal axis

of the bell cranks 70, or 71, of which the arm is part, this construction being for the purpose described later.

One arm of the bell cranks 77 and 78 and also the single arm of the levers 79 and 80 is recessed or hollow, like the arm of the bell cranks 70 and 71 and, in the recess 95 of each of the hollow arms or levers 77, 78, 79, 80, a trolley is provided which travels each within the recess of its arm to change the length or radius of the arc of angular movement of the trolley. The trolleys are each connected by one end to a flexible connection by which the valve buckets are moved.

The trolleys within the hollow arms of the bell cranks 77, 78 and hollow levers 79, 80 consists of a pin or shaft 111 secured in the lower end of the screw threaded adjusting rods 106 and 107, 108 and 109 and on each of the projecting ends of the pins 111 is a wheel or roller 112.

Straps 113, 113 having holes through which the pins project, are provided between each wheel 112 and the adjacent side of the boss on the end of the rods 106, 107, 108, 109 and these straps project through the open side of the recessed or hollow arms 77, 78, 79 and 80 and have a thimble thereon to which is fastened one end of one of the flexible members connecting the trolleys and the reversing valve buckets. The screw threaded upper ends of the adjusting screws 106, 107, 108, 109 project upwardly through slots or openings in the floor of the charging platform 40, through one of the hollow stands 110, and through a flanged internally threaded nut 114 which is rotatably secured to a swivel pin 115 extending through the pairs of lugs or ears 116 on the top of each of the stands 110. A hand wheel 117, 118, 119 or 120 which is keyed or otherwise fastened to each of the flanged nuts 114 provides a convenient means for turning the nuts in raising and lowering the screws lengthwise to adjust the position of the trolleys on the lower end of the rods 106, 107, 108 or 109 toward and away from the pivotal axis of its arm 78, 79, 80 or 81.

The trolley in the hollow arm of the bell crank 77 (to the left of the center of the drawing in Figs. 2 and 4) is connected to one end of a rope or other flexible connection 121 which passes over the sheave wheel 122 that is suspended by a bracket 123 from the charging floor 40, this flexible connection 121 being secured by its other end to the lifting bucket 64 of the gas valve and the trolley in the hollow lever arm 79 (also on the left in Figs. 2 and 4) is connected to one end of a similar flexible connection 124 which passes over a sheave wheel 125 suspended by the bracket 126 from the charging floor, this flexible connection 124 being attached by its other end to the valve bucket 61 of the combustion valve at this end of the fur-

- nace. The trolley in the hollow arm of the bell crank 78 (to the right in Figs. 2 and 4) is likewise connected to one end of a flexible connection 127, which, after passing over the 5 sheave wheel 131 which is suspended from the charging floor by a bracket 129, is connected at its other end to the bucket 62 forming the stack valve and the trolley for the hollow lever or arm 80 is fastened to one 10 end of a flexible connection 130 which passes over the suspended sheave wheel 128 and is secured by its other end to the bucket 63 forming the gas valve for this end of the furnace. The trolley on the hollow arm of 15 the bell crank 70 is operatively connected to one end of a rope or flexible connection 132. This rope extends downwardly and after 20 passing over the sheave wheels 133 and 134 which are pivotally mounted on the bracket 135 suspended from the charging floor 40, is attached by its other end to the mushroom valve 28. The trolley in the hollow arm of the bell crank 71 is likewise connected to one 25 end of a flexible connection 136 which extends downwardly, then passes over the sheave wheels 133, 134 suspended from the floor 40 by the bracket 137 and is fastened by its other end to the other mushroom air 30 valve 29.
- Secured between the under side of the furnace charging platform and the floor of the pit beneath this floor are horizontally extending girders forming stationary supports 138, and 139 and rotatably mounted on one 35 end of each of these supports is a pair of sheave wheels 140, 141, or 142, 143. On the opposite end of each support 138 and 139 is a rotating rope drum 144 or 145. Fastened by one end to the underside of 40 the floor of the charging platform 40 are ropes or cables 146 and 147 each of which extends downwardly and, after passing under its sheave wheel 141 or 142 on the support 138 or 139 is wrapped around the 45 grooved drum 144 or 145 and is fastened thereto by its other end. Also fixed by one end to the grooved drums 144, 145 are ropes 148 and 149 which, after being wound or wrapped around the drum (in the reverse 50 direction to that of the rope 146 or 147) passes over the sheave wheel 142 or 143 and then extends downwardly and is fastened by one end to one or the other of the two 55 damper valves 31, 32 by which the flow of burned gases or products of combustion from the air regenerators 4 and 5 through the stack flue 14 to the stack 15 is regulated and shut off.
- Secured by one end to the double groove 60 sheave wheel 66 on the shaft 46 of the reversing gear are ropes 150 and 151 each of which passes over the idler sheave wheels 152, 152 on the floor 40 and then extends downwardly and then upwardly so as to 65 form a loop, these ropes being secured by one end to one or the other of the rope drums 153 which form part of the adjusting mechanism located on the charging floor 40 for the damper valves 31, 32.
- The drums 153 are rotatably mounted each 70 on a shaft 154, (see Fig. 14) carried in bearings 155 on each of the stands 160 and each drum has a spur gear 161 formed integrally on one end thereof and meshing with a spur pinion 162 in the stands 160, these spur pinions 162 being mounted on an idler shaft 163. Formed integrally with or otherwise secured to the pinions 162 is a spur gear 164 which meshes with a spur pinion 165 which is keyed on the shaft 154 so as to be rotated 75 thereby. A ratchet wheel 166 on the shaft 154 and a pawl 167 on the side of the stands 160 co-act to hold the drum 153, and connecting gears against rotation and each of the shafts 154 which project through one 80 of the bearings 155 to the outside of the stands 160, is provided on its screw threaded outer end, with a hand wheel 169 or 170 for moving the friction disk 171, which is keyed on each shaft 154 into and out of frictional 85 engagement with the friction disk 168 forming 90 part of each ratchet wheel 166.
- Suspended within the loops formed by the hanging strands of rope 150, 151 are the vertically movable floating sheave mechanisms, by which the lifting movement of the valves 31 and 32 is varied to lessen or to increase the extent of opening movement of these valves. Each of the two floating sheave mechanisms Fig. 15 is provided with a suspension sheave wheel 172 which engages with the loop of one or the other of the two supporting ropes 150, 151, the wheel 172 being rotatably secured between the sides of 95 the carriage 173 forming part of each floating sheave mechanism.
- Secured on each of the carriers 173 by means of a pin or stub shaft 174 is a second sheave wheel 175 which is arranged to engage with the rope 148 or 149 extending between the drum 144 and opposite sheave wheel 140 and 142 on the horizontal supports 138, 139. Also secured by a pin or stub shaft 174, on the opposite side of each carriage 173 is another sheave wheel 176 100 110 which operatively engages with the other rope 146 or 147 on the respective supports 138 and 139, which rope extends between the drums 144 and the sheave wheel 141 or 143 on its support 138 or 139.
- The mechanism for operating the valve 31 is the same as that for the valve 32 and this floating sheave mechanism and connections can be applied to any of the several valves in operating the valves in lieu of the other valve lifting mechanism shown. In other words the lifting mechanism for the valves 31 and 42 is applicable for use in actuating the valves 61, 62, 64, 65 or the valves 28, 29 when desired. Adjustably secured on 115 120 125 130 135 140 145 150 155 160 165 170 175 180

the periphery of the crank disk 89 of the reversing mechanism is a cam surface 177 forming stop. This stop 177 is arranged, when the crank shaft 46 on which the crank disk 89 is mounted reaches its stopping positions, to engage alternately, (depending upon the direction of rotation,) with the end 178 or 179 of one of the levers 180, 181 forming part of the quick-break switches 182 and 183 mounted on one side of the stand 43 of the reversing mechanism below the crank disk 89. When the anti-friction roller 184 on the ends 178, or 179 of the levers 180 and 181 are engaged by the cam surface 177 the other end of the lever 180 or 181 is lifted so as to break the connection between the contacts 185 and 186, or contacts 187 and 188, as the case may be, and as these contacts are in the circuits leading from a source of electric current, through a hand operated controller to the driving motor 55, when the ends 178 or 179 of the levers are engaged by the cam surface 177, the circuit is broken and remains broken until the lever is again disengaged from the cam surface 177.

In the operation of our improved apparatus the flexible connections to the various valves are first adjusted to length and secured in adjusted position so that when the operating mechanism is at rest in one extreme position or the other the series of valves will be properly in open or closed position. Assuming that the furnace is in operating condition, the counterweighted stack damper 30 is or will have been adjusted into position to create and maintain the right amount of draft through the furnace and over the furnace hearth under normal conditions. The valves are shown in the drawings in the position in which they are placed for supplying gas and air to the regenerators 2 and 3 on the left hand side of Figs. 1 and 2 and for conducting the burned gases or products of combustion from the furnace through the regenerators 4 and 5 at the right hand side of the furnace. Stated in another way both of the regenerators on the right hand side of the furnace, in Figs. 1 and 2, are being heated by the products of combustion passing therethrough from the furnace hearth to the stack, while in the same time interval, the regenerators on the left hand side of these figures are being employed to heat the incoming fuel gas and air in their passage therethrough into the furnace in which they are mixed and burned. When the draft on the furnace requires changing, the stack damper 30 is raised or lowered the distance necessary to increase or decrease the amount of draft as is desired, and as changes in the position of the stack damper are only necessary at infrequent intervals this damper is manually operated through the medium of a winch or other suitable lifting mechanism, at such times. Should it become necessary or desirable to increase or decrease the volume of air passing through the air damper valves into the air regenerators within a given time interval, the mushroom valves 28 and 29 will be raised or lowered by turning the hand wheels 103 or 104 on the arms of the bell cranks 70 and 71 which moves the trolley in the hollow arm and raises or lowers the mushroom valves 28 and 29 depending upon the direction in which the hand wheels are turned. When the trolley is moved toward the pivotal center of the arm, the arc of angular movement of the trolley is lessened and when moved toward the swinging end of the arm the arc of angular movement of the trolley is increased so that it is made possible to vary the lifting movement of the valves from the maximum stroke to zero. To vary the amount of draft through the air regenerators relative to that through the gas regenerators in the regenerators then being heated by the passage of the products of combustion therethrough, the hand wheel 169 or 170 is turned to change the relative lengths of the loops in the ropes 150, 151 supporting the floating sheaves 172 and by increasing the length of these loops, the sliding damper valves 31 or 32 on the end of the ropes are lowered. Shortening the length of the loop in the rope 150 or 151 by turning the hand wheels 169 and 170 in the opposite direction lifts the damper valve and results in an increase in the draft through the regenerators. In all cases, in reversing the furnace the valves will move sufficiently to come into closing position.

The gas valve buckets 64 and 65 ordinarily will be adjusted to full open position but when it is desired to lessen the volume of the column of gases passing to the gas regenerators, the hand wheel 117 or 118 is turned to lift or raise the rope carrier in the hollow arm of the bell crank 77 or lever arm 80, which movement shortens the radius of the arc movement of the rope carrier and lessens the stroke of the gas valve bucket 64 or 65 in the valve casings. As the extreme downward position of the valve buckets is such as to always close the valves, a slight difference in the length of the stroke of the rope carrier results in lessening the opening movement and thereby lessens the area of the passage when the bucket is in open position. The extent of movement of the valve buckets 64 and 65 is lessened to the desired extent and even to zero in the same manner as heretofore described in connection with the mushroom valves 28 and 29. The combustion valve buckets 61 and 62 are moved and the stroke thereof is varied in the same manner, by adjusting the carrier in the hollow lever arm 79 and bell crank 80 through the medium of the hand wheels 117 and 118. The rope carriers can be moved within

the hollow arms on the pivotal center of these arms and when in this position the swinging movement of the arms and bell cranks will not move the carriers and ropes connected thereto. In such cases, there will not be any lifting movement of the valves whatever. When the furnace is "reversed" to change the direction of flow of air and gases through the furnace, the controller completing the circuit to the motor 55 is placed in closed position to operate the reversing motor in the right direction. The safety switches 182, 183 will act to prevent the motor turning in the wrong direction as the circuit last used in driving the motor remains open owing to the cam surface 177 on the crank disk 89 being in lifting engagement with one or the other of the rollers 184 on the levers 180, 181 forming part of these switches. When the switch 182 is closed, the motor 55 is started and, through the worm 52 and worm shaft 50, rotates or moves the crank shaft 46 through one half of a revolution. As the half revolution is completed the stop 177 on the disk 89 engages with the roller 184 on the arm 179 of the safety switch 183 (now in the completed circuit) and opens this switch to break the circuit, in which position it is held and remains (for an indefinite time interval) until the motor is caused to rotate in the opposite direction, by manually throwing the controller into the reverse position. The cranks, 60, 63, worm wheel 53 and the rope sheave wheel 62 are made of sufficient size to make one half of a complete revolution of the shaft 46 sufficient to move the valves, through their maximum lifting movement in opening and closing the valves, and the adjusting mechanism enables a variable opening movement of the valves to be obtained with a constant stroke of the valve reversing mechanism. When the crank shaft 46 has moved to its extreme position in one direction from its extreme position in the opposite direction the combustion valve 62 and stack valve 32 on one (the right hand end) of the furnace will be closed and the air valve 29 and gas valve 63 on this end of the furnace will open. Simultaneously with the closing movement of the combustion valve and stack valve and opening movement of the air and gas valves, the combustion valve 61 and stack valve 31 on the other end of the furnace will open and the gas valve 64 and air valve 28 will close, so that all of the valves are simultaneously manipulated and the reversal of the furnace is thereby effected mechanically by starting the driving motor 55 in operation. When the furnace is next reversed, the controller is moved manually to complete the circuit through the motor 55, and through the switch 183 which is now closed. The above described operations are then repeated but

in the opposite direction to "reverse the furnace" when the motor is caused to move the reversing mechanism in the opposite direction.

Adjustment of the various valves is made from time to time as found necessary by turning the adjusting hand wheel operatively connected to the operating mechanism for each of the series of valves.

The advantages of our invention will be appreciated by those skilled in the art to which our invention relates. Instead of moving successively the valves are all simultaneously moved mechanically into open and closed positions to reverse the flow of air and gas through the furnace and the possibility of accidents or delays due to setting the valves improperly is avoided and prevented. The necessity of operating the valves manually and the loss of time occasioned thereby are overcome. The apparatus is simple, is readily repaired in case of need and is easily and cheaply maintained in operating condition.

Modifications in the construction and arrangement of the parts may be made without departing from our invention. The apparatus is adapted for use in manipulating a portion only of the valves. The adjusting mechanism whereby the stroke or opening and closing movements of the valves is varied is applicable to a single valve. The relative location of the parts may be changed and other variations in the construction may be made within the scope of the appended claims.

We claim:

1. A furnace valve operating mechanism a valve, a rocking arm, means for actuating said arm, and flexible means connecting the valve to the rocking arm, said means being adjustable on the arm to vary the opening movement of said valve from zero to a maximum.

2. A furnace valve operating mechanism comprising a plurality of valves, rocking arms, means for simultaneously actuating said arms, and means connecting the valves to the arms, said connecting means being independently adjustable to vary the extent of movement of said valves from zero to a maximum.

3. A furnace valve operating mechanism comprising a plurality of pairs of valves, swinging arms for actuating the valves, means connecting the valves to the swinging arms, said means being adjustable on the arms to vary the extent of movement of the valves from zero to a maximum and means for simultaneously swinging said arms to move the valves in opening and closing.

4. A furnace valve operating mechanism comprising valves, rocking arms for actuating said valves, means operatively connecting the arms to the valves, a shaft for

- rocking said arms, a worm wheel on the shaft, a worm for actuating the worm wheel, a motor for actuating the worm, means connecting the arms for actuating said arms simultaneously and in opposite directions in opening and closing the valves and means for automatically stopping the motor, at the end of the opening and closing movement of said valves.
10. 5. A furnace valve operating mechanism comprising a valve, a swinging arm adjustably connected to said valve, a crank shaft operatively connected to the swinging arm, a worm wheel on the shaft, a worm for actuating the worm wheel, a motor for actuating the said worm and means for automatically stopping the motor after a predetermined amount of travel of said valve.
15. 6. A furnace valve operating mechanism comprising reversing valves, swinging arms for actuating said valves, means for connecting the valves to the arms, means for actuating said arms to simultaneously move the valves, and means for independently adjusting the valve connection on each arm to vary the relative movement of the valves, said adjusting means being adapted to regulate the movement of the valves from zero to a maximum.
20. 7. A valve operating mechanism comprising a base, having shaft bearings thereon, a crank shaft mounted in said bearings, said shaft having a plurality of cranks, and a crank disk thereon, a shaft driving motor, a worm and worm wheel operatively connecting the motor and crank shaft, swinging arms operatively connected to the cranks, and the crank disk, flexible connections securing a valve to each of said swinging
25. 40. arms, and means connecting the arms in pairs whereby the arms are actuated simultaneously to move the valves in opposite directions in opening and closing.
8. A valve operating mechanism comprising a base, having shaft bearings thereon, a crank shaft mounted in said bearings, said shaft having a plurality of cranks, and a crank disk thereon, a shaft driving motor, a worm and worm wheel operatively connecting the motor and crank shaft, swinging arms operatively connected to the cranks on said shaft and crank disk, flexible connections securing a valve to each of said swinging arms, means connecting the arms in pairs whereby the valves are moved simultaneously and in opposite directions in opening and closing and means for adjusting said flexible connections on said arms to vary the extent of movement of the valves attached thereto.
30. 45. 50. 55. 60. 65. 70. 75. 80. 85. 90. 95. 100. 105. 110. 115. 120. 125. 130. 9. A valve operating mechanism comprising a base, having shaft bearings thereon, a crank shaft mounted in said bearings, said shaft having a plurality of cranks, a crank disk and a double groove sheave wheel thereon, a shaft driving motor and a worm and worm wheel operatively connecting the motor and crank shaft, swinging arms operatively connected to the cranks, and crank disk, flexible connections securing a valve to each of said swinging arms, and to each groove of the sheave wheel and means for adjusting said flexible connections to vary the extent of movement of the valves attached thereto.
10. A valve operating mechanism comprising a base, having shaft bearings thereon, a crank shaft mounted in said bearings, said shaft having a plurality of cranks, a crank disk and a double groove sheave wheel thereon, a shaft driving motor and a worm and worm wheel operatively connecting the motor and crank shaft, swinging arms operatively connected to the cranks, and crank disk, flexible connections securing a valve to each of said swinging arms, and to each groove of the sheave wheel, and means for independently adjusting said flexible connections to vary the extent of movement of the valves attached thereto.
11. In a furnace valve operating mechanism the combination of a flexible connection fixed at one end and having a valve suspended from the other, means for forming a loop in said flexible connection thereby lift the valve suspended therefrom, and means for changing the length of the loop to vary the lifting movement of the valve.
12. A valve operating mechanism comprising a pair of fixed pulleys, a pair of fixed drums, a flexible connection extending from one drum over one of said pulleys, a second flexible connection extending from the other drum under the other pulley, and having its end fixed above the pulley, the end of the flexible connection extending over the one pulley having a valve suspended therefrom, a movable carrier having pulleys thereon arranged to engage said flexible connections between the fixed pulleys and drums and means for lifting the carrier and to form loops in said flexible connections and thereby rotate said drums and lift said valve.
13. A valve operating mechanism comprising a pair of fixed pulleys, a pair of fixed drums, a flexible connection extending from one drum over one of said pulleys, a second flexible connection extending from the other drum under the other pulley and having its end in fixed position above the pulley, the end of the flexible connection extending over the one pulley having a valve suspended therefrom, a movable carrier having pulleys thereon arranged to engage said flexible connections between the fixed pulleys and drums and means for lifting the carrier to form loops in said connections and thereby rotate said drums and lift said valve, said

lifting means being adjustable to vary the extent of lifting movement of said valve.

14. A valve operating mechanism comprising a pair of fixed pulleys, a pair of fixed rope drums, a rope extending from one drum over one of said pulleys, a second rope extending from the other drum under the other pulley, and having one end secured in fixed position above the pulley, the end of the rope extending over one pulley having a valve suspended therefrom, and a movable carrier having means thereon arranged to engage said ropes between the pulleys and drums, a rope having a loop therein from which the carrier is suspended, and means on one end of said looped rope for moving the rope to shorten the loop therein and thereby lift the valve.

15. A valve operating mechanism comprising a pair of fixed pulleys, a pair of fixed rope drums, a rope extending from one drum over one of said pulleys, a second rope extending from the other drum under the other pulley and having one end adjustably secured in a stationary position above the pulley, the end of the rope extending over the one pulley having a valve suspended therefrom, and a movable carrier having pulleys thereon arranged to engage said ropes between the fixed pulleys and drums, a rope having a loop therein from which the carrier is suspended, means on one end of said looped rope for moving the rope to shorten the loop therein and thereby lift the valve, and means on the other end of said rope to shorten and lengthen the loop to vary the extent of lifting movement of said valve.

16. A furnace valve operating mechanism comprising a series of valves, a rocking arm for actuating each of said valves, means operatively connecting the arms to the valves, a shaft for rocking said arms in unison, a worm wheel on the shaft, a worm for actuating the worm wheel and shaft, a motor for actuating the worm, means connecting the arms for actuating said arms simultaneously and in opposite directions in opening and closing the valves, and switches forming means for stopping the motor at the end of the opening and closing movement of said valves, said switches being arranged to automatically set in stopping the motor to reverse the direction of rotation of said motor when again started.

17. A furnace valve operating mechanism comprising a valve, a swinging arm adjustably connected to said valve, a crank shaft rotatively connected to the swinging arm, a worm wheel on the shaft, a worm for actuating the worm wheel, a motor for actuating the worm, and means for stopping the motor after a predetermined amount of valve, said means including switches arranged to automatically set in stopping the

motor to reverse the direction of rotation of the motor when again started.

18. A furnace valve operating mechanism, comprising a valve, a rocking arm, means for actuating said arm, and flexible means connecting the valve to the rocking arm, said means being adjustable on the arm to vary the operative movement of said connecting means and valve in opening the valve from zero to a maximum. 70

19. A furnace valve operating mechanism comprising a valve, a rocking arm, means for actuating said arm, flexible means connecting the valve to said rocking arm, said means being adjustable on the arm to vary the opening movement of said valve, and means on said arm for adjusting the valve connecting means thereon to vary the lifting movement of the valve connecting means and valve from zero to a maximum. 85

20. A furnace valve operating mechanism comprising a plurality of valves, rocking arms, means for simultaneously actuating said arms, and means connecting the valves to the arms, said connecting means being independently adjustable to vary the extent of movement of the connecting means and valves from zero to a maximum. 90

21. A furnace valve operating mechanism comprising a plurality of pairs of valves, 95 separate swinging arms for actuating the valves, means connecting each valve to its swinging arm, said means being adjustable on the arms to vary the extent of lifting movement of the valves from zero to a maximum, and means for simultaneously swinging said arms to move the valves in opening and closing.

22. A furnace valve operating mechanism, comprising a plurality of pairs of valves, 105 separate swinging arms for actuating the valves, means connecting each valve to its swinging arm, said means being arranged to vary the extent of movement of the valves from zero to a maximum, means for simultaneously swinging said arms to move the valves in opening and closing the valves, and means connecting the valves in pairs whereby one valve in each pair is opened 110 when the other is closed. 115

23. A furnace valve operating mechanism comprising valves, rocking arms for actuating said valves, means operatively connecting the arms to the valves, a shaft for rocking said arms, a worm wheel on the shaft, a worm for actuating the worm wheel, a motor for actuating the worm, means connecting the arms for actuating the worm, means connecting the arms for actuating said arms simultaneously and in opposite directions in opening and closing the valves, and means for automatically stopping said motor when the valves moving into closed position reach such closing position. 125

24. A furnace valve operating mechanism 130

comprising valves, rocking arms for actuating said valves, means operatively connecting the arms to the valves, a shaft for rocking said arms, a worm wheel on the shaft, 5 a worm for actuating the worm wheel, a motor for actuating the worm, means connecting the arms for actuating the worm, means connecting the arms for actuating said arms simultaneously and in opposite 10 directions in opening and closing the valves, means for automatically stopping said motor when the valves moving into closed position reach such closing position, and means for mechanically reversing the direction of 15 rotation of the motor each time the motor is stopped.

25. A furnace valve operating mechanism comprising reversing valves, separate swinging arms for actuating said valves, means 20 for connecting each valve to its arm, means for actuating said arms to simultaneously

move the valves, and means for independently adjusting the valve connection on each arm to vary the relative movement of the valves, said adjusting means being adapted to regulate the movement of the valves from zero to a maximum.

26. In a valve operating mechanism the combination of a flexible connection fixed on one end and having a valve suspended from the other, and means for shortening said flexible connection to thereby move the valve on the end thereof, said means being adjustable to vary the extent of lifting movement of the flexible connection.

In testimony whereof, we have hereunder set our hands.
